CLAIM

The ornamental design for a concrete test piece forming mold, as shown and described.

DESCRIPTION

FIG. 1 is a right front top perspective view of a concrete test piece forming mold;

FIG. 2 is a front elevational view thereof; the rear being symmetrical to the front;

FIG. 3 is a right side elevation view thereof, the left side being symmetrical to the right side;

FIG. 4 is a top plan view thereof;

FIG. 5 is a bottom plan view thereof;

FIG. 6 is a sectional view thereof taken along the line 6—6 in FIG. 2;

FIG. 7 is a sectional view thereof taken along the line 7—7 in FIG. 2; and,

FIG. 8 is a view showing the state of use thereof by way of reference.

The broken line showing of concrete is for illustrative purposes only and forms no part of the claimed design.
